UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL MACHINE.

1,231,879.

Specification of Letters Patent.

Patented July 3, 1917.

Application filed September 18, 1915. Serial No. 51,328.

To all whom it may concern:

Be it known that I, ALFRED W. F. GUEST, a citizen of the United States, residing at Brooklyn, in the county of Kings and State 5 of New York, have invented certain new and useful Improvements in Typographical Machines, of which the following is a specification, reference being had therein to the accompanying drawing.

10 My invention has reference to typographical machines, such as linotype machines of the general organization represented in U. S. Letters Patent to O. Mergenthaler, No. 436532, wherein matrices representing the 15 various characters to appear in print are stored in a channeled magazine and are released therefrom one at a time through the action of escapement devices controlled by finger keys. In these machines, it is common to store the more frequently used characters, such as the letter "e," in two or more channels of the magazine, and to provide mechanism whereby a single finger key may effect their release from the different channels 20 in alternation or succession. Such a mechanism is shown in the U. S. Letters Patent to D. S. Kennedy, No. 1,092,150, wherein the change from one channel to another is controlled by an automatic vibratory dog secured to the rear end of the finger key and which serves through intermediate parts to actuate the escapements of the duplicate channels in the required order.

My present invention follows somewhat 35 along the lines of the Kennedy patent and aims to simplify and render more certain the action of the parts, to which end, generally speaking, the vibratory dog is mounted upon a power-operated member controlled 40 in its action by the finger key, as distinguished from attaching the dog directly to the key, as in the Kennedy patent. When thus arranged, the dog is controlled with greater certainty and allows the key to be 45 operated by the same light and rapid touch which characterizes the remaining keys of the keyboard. Another feature of the invention consists in arranging the automatic dog so that it may be rendered inactive at 50 will to permit the release of matrices from one magazine channel continuously until a change to another is desired.

In the accompanying drawing, I have shown my invention merely in preferred

form and by way of example and as applied 55 to the particular style of machine mentioned, but obviously many variations and alterations may be made therein and in its mode of application, which will still be comprised within its spirit. Thus, it may be 60 applied to other forms of escapements or matrix releasing devices, and to other styles of machines, such as typesetters, and the like. Generally speaking, I desire it to be understood that I do not limit myself to 65 any specific form or embodiment, except in so far as such limitations are specified in the claims.

Referring to the drawing:—

Figure 1 is a detached perspective view, 70 partly in section, of the escapement actuating mechanism of a linotype machine having my invention applied thereto;

Figs. 2 and 3 are detached detail-views showing the parts in different relative positions;

Fig. 4 is a section on the line 4—4 of Fig. 2; and

Fig. 5 is a section on the line 5—5 of Fig. 4.

The matrices X are stored in the channeled magazine A and are released therefrom by the escapements B, one for each channel of the magazine, and which are actuated by the vertical reeds C, the two outermost ones (which alone are concerned with the present invention) being designated C¹ and C². These escapement reeds are operated by the yokes D, (only one of which is shown herein) provided with the lifting 90 cams or eccentrics D¹ adapted to be thrown into engagement with the constantly rotating roller D² by the yoke sustaining dogs E, when the latter are tripped by the vertical slides F upon the actuation of the finger keys G. The parts so far described are of the usual construction and may be found in U. S. Letters Patent to P. T. Dodge, No. 530,931. The single cam yoke D shown herein is controlled by a finger key bearing 100 the letter "e" and serves through parts, presently to be described, to actuate one or the other of the reeds C¹ and C² to release matrices having the same character from the two outermost magazine channels.

In the present instance, and according to my invention, the alternate action of the reeds C¹ and C² is effected through the me-

dium of a vertical longitudinally-movable member K arranged above the cam yoke D in position to be actuated thereby, and suitably supported and guided in a fixed bracket 5 J, which also gives support to the reeds C¹ and C². The member K is provided at its rear edge with a vibratory dog H arranged in a recess K² and mounted upon a pivot stud K³, so as to be brought into engaging 10 relation to one or the other of the reeds C¹ and C². The dog is of the same construction as disclosed in the Kennedy Letters Patent before referred to, being formed with a transverse slot H³ through which the stud 15 K³ passes, and provided with shoulders H¹ and H² on opposite sides of the slot, and having pointed ends H⁴ and H⁵, the former being arranged to coöperate with an oppositely pointed or inverted V-shaped block M¹. 20 With the parts thus constructed and arranged, when the key G is depressed, the yoke D is raised by the engagement of its cam D¹ with the constantly driven roller D², and shifts the member K upwardly. This 25 upward movement of the member K is communicated to one or the other of the reeds C¹ and C² through the engagement therewith of the corresponding shoulder H¹ or H² of the dog H, and during such movement 30 the lower end H⁴ of the dog slides along one or the other of the beveled faces of the V-shaped block M¹ until the member K is lifted to its full extent, when the dog is rocked and shifted bodily toward the right or left as 35 the case may be to locate its pointed end on the opposite beveled face of the block M¹, which then, during the return movement of the member K, brings the other shoulder of the dog in engaging relation to the corre- 40 sponding reed. The particular mode of action of the dog is fully explained in the Kennedy patent, to which reference may be had, if desired, for any further description.

The present arrangement differs from that 45 of Kennedy in the respect that the automatic dog is located upon the longitudinally movable member K instead of upon the finger key, as a result of which the dog is controlled positively under the influence of 50 the power-operated cam yoke D, thus insuring greater certainty and uniformity in its action and without affecting the usual sensitive touch of the key. For instance, the relatively prolonged actuation of the member K allows greater time for the lateral shifting of the dog, and the upward shifting of the member to the same extent at each actuation also insures the lifting of the dog the required distance for its proper coöperation 55 with the block M¹.

In order to avoid the automatic shifting of the dog H, so that it may be caused to actuate only one of the escapement reeds C¹ and C² under repeated actuations of the 60 finger key, the block M¹ is carried by a slide

M so as to be movable instantly thereby to an inactive position when desired. The movement of the slide is effected by an eccentric M² engaging in a recess in its rear face and fast upon a short shaft M³ exposed at the front of the machine, and provided with an operating handle M⁴, whose turning in one direction or the other shifts the block M¹ into active or inactive position, where it is held by spring fingers M⁶ engaging in recesses in a roller M⁵ on the shaft (see Figs. 4 and 5). In Figs. 2 and 3 the block M¹ is shown in inactive position, causing the dog H to operate as follows: As illustrated in Fig. 2, the dog stands with its shoulder H¹ in engaging relation to the reed C¹ and with its pointed end H⁴ located to the left of the V-shaped block M¹, so that when the dog is raised by the upward movement of the member K, its pointed end slides along the bevel at the left of the block, the dog in the meantime turning about its pivot K³ to the position indicated in Fig. 3. When the member K completes its upward movement, the lower end of the dog stands above the pointed end of the block M¹, and normally these parts would overlap so as to cause the dog to slide down the bevel at the right of the block, but owing to the altered position of the block M¹, the lower end of the dog cannot overlap it, as indicated by dotted lines in Fig. 2, so that when the dog is lowered by the return of the member K, it slides down the same beveled surface along which it was raised and is thereby shifted back to its original position. As a result, the dog is caused to actuate the reed C¹ each time the finger key is operated. The effect of this arrangement is that the automatic mechanism which controls the delivery of the matrices from alternate magazine channels is rendered active or inactive at will. One of the advantages of the arrangement is the capability of interchanging magazines in different machines, that is, it allows the use of a magazine without an extra channel for duplicate matrices in a machine equipped with the present or similar automatic shifting arrangement. 100

As previously stated, I have shown my invention merely in preferred form and by way of example, and obviously many changes and modifications therein will suggest themselves to those skilled in the art without departure from its scope. 110

Having thus described my invention, its construction and mode of operation, what I claim and desire to secure by Letters Patent of the United States is as follows:

1. In a typographical machine, the combination of two independently operable reeds, a reciprocating member provided with an oscillating dog movable into engaging relation to the reeds alternately, power-driven mechanism for operating said mem- 125

- ber, and a finger key controlling the action of said mechanism.
2. In a typographical machine, the combination of two independently operable reeds, a reciprocating member provided with an oscillating dog movable into engaging relation to the reeds alternately, means for reversing the position of the dog at each operation of said member, power-driven mechanism for operating the member, and a finger key controlling the action of said mechanism.
3. In a typographical machine, the combination of two reeds, a power-operated member provided with a vibratory dog to engage and actuate the reeds alternately, and relatively stationary means coöoperating with the dog to control its operation.
4. In a typographical machine, the combination of two reeds, a power-operated member provided with a vibratory dog having a pair of shoulders to engage the reeds, and automatic means for shifting the dog in opposite directions to locate its shoulders alternately in engaging relation to the reeds.
5. In a typographical machine, the combination of the reeds C¹ and C², the longitudinally-movable member K provided with the slotted dog H having the shoulders H¹ and H², and the pointed end H⁴, and the pointed block M¹ coöoperating with the pointed end of the dog, in the manner and for the purpose described.
- 35 6. In a typographical machine, the combination of means for effecting the deliv-

ery of matrices from a channeled magazine, automatic mechanism for controlling said means to cause the delivery of matrices alternately from different channels of the 40 magazine in a definite and predetermined order, and means whereby the said automatic mechanism may be rendered inactive at will.

7. In a typographical machine, the combination of two actuating devices, a single finger key, automatic mechanism for causing the key to operate said devices alternately in a definite and predetermined order, and means whereby said mechanism 50 may be rendered inactive at will so as to allow the finger key to operate a selected one of the actuating devices alone at successive actuations.

8. In a typographical machine, the combination of two reeds, a reciprocating member provided with a vibratory dog to engage and actuate the reeds alternately, automatic mechanism for controlling the action of said dog, and means whereby said 60 mechanism may be rendered inactive at will.

9. In a typographical machine, the combination of the two reeds C¹ and C², the actuating member K provided with the dog 65 H, the block M¹ controlling the action of the dog, and the movable slide M carrying the block M¹.

In testimony whereof, I have affixed my signature. 70

ALFRED W. F. GUEST.
